AIR HEATER

Joseph Schmid, Cleveland Heights, Ohio

Application June 22, 1937, Serial No. 149,754

4 Claims. (Cl. 126—101)

This invention relates to an air heater which will be safe from explosion, gases and fire, and has for the primary object the provision of an efficient and inexpensive device of this character which will have a wide range of uses, requiring a minimum amount of space for installation, and which will discharge a maximum amount of heated air and distribute the latter efficiently over a large area and may be economically operated due to its low consumption of fuel.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a top plan view partly in section illustrating an air heater constructed in accordance with my invention.

Figure 2 is a vertical sectional view illustrating the same.

Figure 3 is a transverse sectional view taken on the line 3—3 of Figure 1.

Figure 4 is a transverse sectional view taken on the line 4—4 of Figure 1.

Figure 5 is a detail sectional view taken on the line 5—5 of Figure 2.

Figure 6 is a side elevation, partly in section, illustrating one of the heating tubes.

Figure 7 is a fragmentary vertical sectional view illustrating an electrical heating element adaptable to the heating tube.

Figure 8 is a plan view illustrating a modified form of heating tube.

Figure 9 is a plan view illustrating another modified form of heating tube.

Referring in detail to the drawings, the numeral 1 indicates an elongated casing in which are located partitions 2 dividing said casing into a heat chamber 3 and combustion chambers 4 and 5. Said partitions have openings to receive heating tubes 6 which extend substantially the full

length of the heating chamber 3 and all enter the combustion chamber 4 while certain of said tubes extend into the combustion chamber 5. Supporting rods 7 are located at one end of the casing and are engaged by hook-shaped elements 8 of the tubes. Said end of the casing has connected thereto a fan housing 9 open to the atmosphere and in which operates a power driven fan 10. Between the open end of the fan housing and the fan 10 is a screen 11 for collecting the foreign

matter from the air drawn in by the fan and

expelled through the heat chamber about the tubes, the latter having spiral ribs 12 formed thereon to cause a swirling movement to the air driven through the heat chamber 3. A discharge pipe 13 is connected with the heat chamber 3 and includes a curved portion terminating in a flared discharge member 14 located laterally of the housing or casing 1 and in a plane thereabove. Deflecting plates 15 are located in the pipe 13 to cooperate with the flared member 14 in distributing the heated air over a large area.

The tubes 6 are filled with a liquid or solution, preferably of water and glycerine or any other fluid suitable for the purpose. The casing has doors 16 to give access to the combustion chambers in which are located gas burners 17. The casing above the combustion chambers is provided with a neck 18 to which a suitable exhaust flue may be connected. Should it not be desired to employ gas as a heating medium, electrical heating units 19 may be adapted to the tube within the combustion chambers. When the device needs less heat for its successful operation, the burner in the compartment 4 may be extinguished. The heat then being conveyed to the heat chamber by the tubes which extend into the chamber 5 and heated by the burner therein.

A partition 20 is located in the heat chamber 3 and extends into the pipe 13 and is located adjacent one of the partitions 2 to form a compartment in which sand may be located to act as heat resisting packing about the tubes where the latter pass through one of the partitions 2. The portion of the partition extending into the pipe 13 acts as a deflector to deflect the hot air upwardly and towards one of the walls of the pipe in which is located an opening to receive the discharge neck 21 of an air moistener 22. The air moistener is in the form of a reservoir supported in the casing 1 and is supplied with liquid by a supply pipe 23 equipped with a float controlled valve 24 acting to maintain the liquid at a predetermined level within the air moistener. The hot air passing through the pipe and passing the discharge neck 21 will draw into the pipe moisture, thereby moistening the heated air prior to escaping from the pipe.

The tubes instead of being straight, as shown in Figure 2, may be of coiled formation, as shown in Figure 8, and indicated by the character 25 or 50 the tubes may be of a shape shown in Figure 9 and indicated by the character 26.

What is claimed is:

1. An air heater comprising a casing including a heat chamber and combustion chambers, heat-

ing tubes extending substantially the full length of the heat chamber and certain of said tubes extending through both of said combustion chambers and the other tubes terminating within one of the combustion chambers, heating means in said combustion chambers for heating the tubes, an exhaust conduit connected with said heat chamber, and means for forcing air to the heat chamber and therefrom by way of said conduit.

2. An air heater comprising a casing including a heat chamber and combustion chambers, heating tubes extending substantially the full length of the heat chamber and certain of said tubes extending through both of said combustion chambers and the other tubes terminating within one of the combustion chambers, heating means in said combustion chambers for heating the tubes, an exhaust conduit connected with said heat chamber, a fan casing connected on said casing and communicating with the heat chamber, and a power driven fan operating in the fan casing.

3. An air heater comprising a casing including a heat chamber and combustion chambers, heating tubes extending substantially the full length of the heat chamber and certain of said tubes extending through both of said combustion chambers and the other tubes terminating with-

in one of the combustion chambers, heating means in said combustion chambers for heating the tubes, an exhaust conduit connected with said heat chamber, a fan casing connected on said casing and communicating with the heat chamber, a power driven fan operating in the fan casing, said heat chamber having a compartment located adjacent the combustion chambers and filled with a pulverized material, said tubes containing a liquid.

4. An air heater comprising a casing including a heat chamber and combustion chambers, heating tubes extending substantially the full length of the heat chamber and certain of said tubes extending through both of said combustion chambers and the other tubes terminating within one of the combustion chambers, heating means in said combustion chambers for heating the tubes, an exhaust conduit connected with said heat chamber, a fan casing connected on said casing and communicating with the heat chamber, a power driven fan operating in the fan casing, said heat chamber having a compartment located adjacent the combustion chambers and filled with a pulverized material, said tubes containing a liquid, and spiral ribs formed on said tubes.

JOSEPH SCHMID.
